UNITED STATES PATENT OFFICE.

LEWIS T. WILCOX, OF PEEKSKILL, NEW YORK, ASSIGNOR TO WILCOX PATENTS CORPORATION, OF PEEKSKILL, NEW YORK, A CORPORATION OF NEW YORK.

OIL HEATER.

Application filed January 26, 1926. Serial No. 83,899.

My invention relates to oil burners for heaters and while it is of very general application to various types of oil heaters, it has, for reasons which will appear, an especially 5 utility with water heaters and will therefore be illustrated and described as embodied in such a heater.

In the usual portable heater of the oil burning type, the upper or drum part may 10 hinge to the base to afford access to the burner for cleaning and repairing and rewicking, but in some forms of heaters it is not practicable to so hinge the drum to the base. For example, in water heaters the 15 connection of the coils in the heater to the water inlet and outlet conduits requires that the heater be stationary and that the casing be immovable relative to the base.

One purpose of my invention is to provide 20 means whereby the burner may be made readily accessible in heaters of the type where the upper part is not hinged to the base, and my invention contemplates mounting the burner upon a swinging base or 25 support which is so hinged to the heater base that the burner is brought clear of the base when the support is swung out.

The burner extends from its support up 30 through an opening in the bottom of the casing. In order to permit the burner to be swung out of the casing the front section of the casing is made removable, and the front 35 of the base is also open. In order that the device may be made to open either to the right or left, depending upon the requirements of its location, I have, in accordance 40 with my invention, provided a hinge construction both for the front section of the casing and for the burner support which permits these parts to be swung either way.

My invention also includes means for permitting the oil pipe to be reversed with respect to the burner base so as to bring the oil reservoir or supply tank on either side 45 of the heater. My invention has other objects and advantages and comprehends various other details and arrangements of parts, as will hereinafter more fully appear.

I shall now describe the illustrated embodiment of my invention and shall thereafter point out my invention in claims.

Fig. 1 is a central vertical section through a heater embodying my invention;

Fig. 2 is a front elevation of the same;

Fig. 3 is a fragmentary view in elevation 55 of the upper part of the heater with the swinging section open so as to expose the inside of the heater;

Fig. 4 is a plan view of the top of the heater; 60

Fig. 5 is a sectional detail of the bottom manifold taken on line 5—5 of Fig. 1;

Fig. 6 is a transverse section through the heater on the line 6—6 of Fig. 1;

Fig. 7 is a transverse section through the 65 base on the line 7—7 of Fig. 2.

The invention is illustrated in a water heater, the main casing 1 of which is cylindrical and has its front section 2, which is substantially half the casing, hinged to open. 70 The lower manifold 3, which is preferably of brass, is oval in shape, as shown in Fig. 5, and is provided at its outer end with a collar or bushing portion 4 which is non-circular in shape and fits in a seat in a boss 5 on the wall of the casing. This prevents the manifold from turning when the heater is being erected. A nut 6 screws on the outer threaded end of the manifold which protrudes through the casing and this nut bears 80 against the outer face of the casing and locks the manifold in place. The inlet pipe 7 is screwed into this manifold.

The upper manifold 8 is oblong, as appears in Fig. 3, and also has a non-circular 85 collar or bushing 9, corresponding to the bushing 4, and fitting into a seat in a boss 10 in the wall of the casing. The nut 11 locks the manifold 8 in its seat in the casing, in the same way that the nut 6 locks the 90 lower manifold in place. The hot water or outlet pipe 12 screws into the manifold 8. There are shown four water coils which connect at their bottom ends with four openings in the cold water manifold 3, and at 95 their upper ends with four openings in the upper manifold 8. Obviously, the number of these coils may be varied according to requirements. They will preferably be arranged in staggered relation so that each turn is over a space between two adjacent coils immediately below. In this way, the 100 hot gases have free access to all the turns of the water coils.

A pipe collar 14 is secured to the back 105 section 1 of the casing, and this leaves the front section 2 free to open and close without interfering with the pipe collar. A

transparent window 15 of mica or other suitable material is secured in a frame in the front section in proper location to afford observation to the flame.

6 The construction and arrangement of the water coils and associated parts as shown and as above described, form no part of my present invention but are described and claimed by me in a copending application, 10 Serial No. 148, 648, filed November 16, 1926. Any suitable type of burner may be used with the device, but I have shown a burner 16 of the type known as the "blue flame burner" which requires a long chimney or 15 casing to induce the necessary draft to make the burner operate properly. In the heater shown, the casing 1 serves as the chimney. The spaces between the coils 15 will be sufficient to allow a free circulation so as not to 20 interfere with the draft.

The burner is mounted upon a swinging support 17 hinged to the base portion 1^a of the casing 1, and the burner extends with its upper end into the bottom of the casing 1 in 25 sufficiently close proximity to the manifold 3. The bottom of the casing is constructed with an integral inward flange or shoulder so as to provide a burner opening 18 only slightly larger than the burner. This leaves 20 a narrow annular space about the burner collar for the passage of air and this construction also prevents the distortion or misplacement of the burner 16 by the improper fitting of the two sections 1 and 2 of 35 the casing.

The base section 1^a of the casing is shown as substantially semi-circular. The swinging burner support 17 is shown as a circular plate or pan, the center of which is depressed 40 and will catch any drippings from the burner. Extending substantially diametrically across the top of this pan 17 and secured thereon by clamps 19 is the oil pipe 20 which connects to an oil supply tank or 45 reservoir (not shown), which is carried on the end of the pipe. A cap 20^a closes the other end of the oil pipe outside of the heater base. The clamps 19 are shown as U-shaped clips with their ends turned out- 50 wardly, one end being inserted through a slit in the top of the pan 17 and the other end being secured by a screw, or otherwise, to the top of the pan. These clips extend over flattened sections of the oil pipe 20, and 55 the burner 16 is secured on these flattened sections in the usual and well known way. Holes through the oil pipe communicate with holes in the feet 16^a of the burner which are clamped to the pipe, and in this 60 way communication is provided between the pipe and the wick chamber of the burner. The burner is secured to the oil pipe by stir- 65 rups or straps 21, the upper ends of which overlap and are tapped with registering screw threaded holes through which passes a

set screw 21^a which is turned down and bears on top of the respective foot 16^a of the burner.

The burner base or pan 17 is releasably hinged to the outside of the base 1^a on both sides of the open front. Each side of the base is provided with two hinge sections 22 and 23, while on opposite sides of the pan 17 are provided a hinge section 24 which is formed on the outer side of an integral arm 75 25 extending outwardly so as to bring the hinge section in cooperative relation with the sections 22 and 23. Removable hinge pins or pintles 26 are provided for each hinge. When the burner is in place, both 80 hinge pins 26 are inserted and the swinging burner support 17 is locked against movement. Either pin 26 may be removed, according to the direction it is desired to swing the support to provide access to the burner, 85 the other pin then serving as the pivot pin. Lugs 27 on the inside of the base serve to guide and position the burner support 17.

In order to permit the burner to be swung out it is necessary that the front section 2 of the casing be opened. For this purpose this section is shown as also hinged releasably on both sides of the casing so as to allow it to be swung in the same direction that the burner is swung. This is oftentimes necessary as by reason, for example, of the location of the heater in a corner. The hinges 28 on the one side are provided with removable pins 29, and the hinges 30 on the other side are provided with removable pins 31. 100

In order to permit the heater to be set up with the oil supply tank on either side of the heater, the connection of the oil pipe 20 to the burner support 17 is such as to allow the pipe to be reversed. The clips 19 are 105 taken out and this releases the oil pipe from the hinged support. The burner also will be reversed on the pipe in case of a reversal of the pipe, so as to keep the wick-adjusting member 32 on the outer side of the burner where it is accessible. This merely requires letting up on the set screws 21^a until the burner feet 16^a are free, and the straps 21 are then moved out and the burner turned around and the straps then brought back 110 and the set screws again turned down.

It is obvious that various modifications may be made in the details and arrangements of parts herein described and illustrated for the purpose of explaining the nature of the invention within the principle and scope of the invention as expressed in the appended claims. 115

I claim:

1. A heater comprising a casing including 120 a base portion, a drip pan constituting a burner mount hinged to the base portion at one side thereof, an oil pipe secured to the mount, and a burner secured to the oil pipe, whereby the mount and parts carried thereby 125 130

can be swung on the hinge to bring the burner outside the base.

2. A heater comprising a casing including a base portion, a burner mount hinged to the base portion at two opposite sides thereof, an oil pipe secured to the mount, and a burner secured to the oil pipe, whereby the mount and parts carried thereby can be swung in either of two directions to bring the burner outside the base.

3. A heater comprising a casing including a base portion, a burner mount fitting within the base portion and hinged thereto at two opposite points, the hinges including removable pintles whereby the mount may be held against rotation or be swung selectively on either hinge, an oil pipe secured to the mount, and a burner secured to the oil pipe.

4. A heater comprising a casing including a base portion having two opposite outside hinge members, a burner mount arranged to go within the base and having hinge members cooperative with those on the base, removable pintles joining the respective hinge members, an oil pipe secured to the mount, and a burner secured to the pipe in coaxial relation with the casing when the mount is within the base.

5. A heater comprising a casing including a base portion, and a burner mount releasably hinged to the base portion at two opposite points, whereby it may be non-rotatively secured to the base portion or may be swung thereon selectively in either of two directions.

6. A heater comprising a casing including a base open unobstructedly for a substantial circumferential portion, a burner mount hinged to the base so that it may be disposed under the casing and swing substantially clear thereof through the open portion, an oil pipe leading from outside the base secured to the mount by means permitting the reversal thereof and so disposed on the mount that its path of movement in both positions is through the open portion of the base, and a burner secured to the pipe.

7. A heater comprising a casing including a base open unobstructedly for a substantial circumferential portion, a burner mount hinged to the base at two opposite points, the hinges including removable pintles whereby the mount may be held within the base against rotation or be swung selectively on either hinge, an oil pipe leading from outside the base secured to the mount by means permitting the reversal thereof and so disposed on the mount that its path of movement in both positions is through the open portion of the base, and a burner secured to the pipe.

8. A heater comprising a casing having a removable front closure and a substantially

restricted burner opening in its bottom and a base portion below said opening with an open front, a burner in the base extending up into the casing through the burner opening and proportioned in size to leave a narrow annular space around the burner in the burner opening, and a support for the burner pivoted to the base so as to allow the burner to be swung out clear of the base through the front openings in the base and casing.

9. A heater comprising a casing having a front opening and a base portion with an open front, a burner in the base extending up into the casing, a closure for the front opening of the casing releasably hinged to the casing on both sides of the opening, and a support for the burner releasably hinged to the base on both sides of its open front, whereby the burner may be rotated clear of the base in either direction through the open fronts of the casing and base.

10. A heater comprising a casing having a removable front closure and a substantially restricted burner opening in its bottom and a base portion below said opening with an open front, a burner support releasably hinged to the base on both sides of its open front so that it may be selectively rotated outside the base in either direction, an oil pipe reversibly secured to the burner support and extending outside the base and so disposed on the support that in either of its reversed positions it swings through the open front of the base as the support is rotated on either hinge, and a burner secured to the oil pipe and extending up into the casing through the restricted burner opening.

11. A heater comprising a casing having a front opening and a base portion with an open front, a burner in the base extending up into the casing, and a support for the burner releasably hinged to the base on both sides of its open front.

12. A heater comprising a casing having a burner opening in its bottom and a base open in front, a burner support pivotally hinged to the outside of the base on one side of the open front, and shaped to fit within the base, and positioning lugs for the burner support on the inside of the base.

13. A heater comprising a casing having an integral inwardly extending flange at its lower end providing a burner opening of restricted size relative to the size of the casing, a base for the casing, and a burner in the base extending up into the casing through the burner opening with a narrow annular space between the burner and the flange.

In witness whereof, I hereunto subscribe my signature.

LEWIS T. WILCOX.
